UNITED STATES PATENT OFFICE.

CHARLES J. MILLER, OF MINNEAPOLIS, MINNESOTA.

STORE-SERVICE APPARATUS.

SPECIFICATION forming part of Letters Patent No. 712,398, dated October 28, 1902.

Application filed December 17, 1900. Serial No. 40,083. (No model.)

To all whom it may concern:

Be it known that I, CHARLES J. MILLER, a citizen of the United States of America, and a resident of the city of Minneapolis, in the 5 county of Hennepin and State of Minnesota, have invented certain new and useful Improvements in Store-Service Apparatus, of which the following is a specification.

My invention relates to store-service apparatus, and particularly to means for stopping the parcel or package carriers of systems employed in store service at the bundle-counter or office-station, and has for its object the provision of means adapted to prevent oscillation of the basket or carrier as it arrives at the station and to take up the impetus and impact of the basket or carrier, so as to minimize the strain upon the wires, fixtures, and cars, prevent the crystallization of the wires 15 caused by such oscillation, and consequently effectuate a material saving of wear, thereby greatly lengthening the life of such apparatus and at the same time prevent noise at such bundle-counter or home-station heretofore incident to the receipt of the carrier at 20 such station.

My object is to provide such means in a simple, cheap, compact, durable, and efficient form and in such form as to be readily applied to carrier systems already installed.

To these ends my invention consists in the provision, in connection with the station-frame, of means whereby as the car arrives at the bundle-counter station and is there 35 stopped all oscillation of the basket or carrier is prevented, the impetus or momentum being taken up by frictional means, whereby all noise is eliminated.

More specifically the invention consists in 40 the combination, with the station, of means in connection therewith whereby the carrier or basket is stopped by frictional contact with said means without noise.

More specifically the invention consists in 45 the combination, with the bundle-station, of means provided in proximity thereto and in the path of the incoming carrier, whereby said carrier comes in contact with said means and the frictional contact of the carrier or 50 basket with said means stops said carrier or basket, taking up its impact and impetus

gradually and noiselessly, relieving all strain from the wires and fixtures.

The invention consists, further, in the constructions and combinations of parts herein- 55 after described, and particularly pointed out in the claims, and will be more readily understood by reference to the accompanying drawings, forming part of this specification, in which—

Figure 1 is a side elevation of a store-apparatus embodying my invention, the carrier being shown in dotted lines in the position in which it stands after its receipt at the station. Fig. 2 is a plan view thereof. Fig. 3 65 is a sectional plan view of the arms or castings which I provide for supporting the friction arms or bars. Fig. 4 is a detail view of one of said arms or castings and the frictional arm grip-piece. Fig. 5 is a sectional view on 70 the line *a a* of Fig. 1.

As shown in the drawings, 2 represents the lever-foot, which is secured in the hanger 3, in turn secured on the plate 4, suspended from the pipe 5. All of these parts may be 75 of the ordinary or any preferred construction, or any means for holding or supporting the lever-foot desired or preferred may be used. The lever 6 is pivoted in the fork of the foot 2, as shown. The wires 14 and 15 80 are attached to the front and rear ends of the lever 6, as shown, respectively. A suitable handle 8 is provided on the lever, by which the same is operated. Two arms or castings 9 of the form shown best in Fig. 4 85 are provided at respective ends with the flanges 10 and the serrated grips 7. These arms are adapted to encircle the lever-foot 2, as shown, and are held in place by suitable bolts and nuts, as shown. The curved friction arms or bars 11 are supported and held between the grips 7 and the serrated plates 12 by four bolts passing through holes in said grips and plates, the grips 7 being serrated to correspond to the inner faces of the 90 plates. The bolt-holes are preferably so spaced as to permit the insertion of the arms or forks 11 in place between the respective pairs of bolts, thus permitting the horizontal and vertical adjustment of the arms or forks 100 therein. The friction arms or forks 11 are preferably covered with leather, rubber, or

other material adapted to deaden the noise, the arms or forks being preferably of wood or spring metal and preferably slightly curved, as shown. The carrier 16 is provided with 5 two pairs of wheels, the upper wheel of each pair adapted to run on the upper wire 14 and the lower wheel of each pair adapted to run against the lower wire 15. These wheels are mounted on axles 17, which are preferably in 10 the form of short bolts, being retained in place by suitable nuts 18. I provide brackets 19 on the sides of the carrier, having outwardly-turned lower ends or lugs 19', adapted to contact with the friction arms or forks 11 15 when the carrier approaches the station. These brackets have slots 20, through which the carrier-axles are passed, and are held in position on the sides of the carrier by the heads of the axles and the nuts 18. Vertical 20 adjustment of these brackets 19 is provided by the slots 20, as shown.

In operation the carrier 16 is propelled toward the bundle-counter station by the operator pulling down the lever 6 by the handle 25 at the outlying station. The wires 14 and 15 are thus separated and the carrier or car impelled toward the home-station. As the carrier passes between the forks 11 the lugs 19' of the brackets 19 ride up on said forks or 30 arms and the carrier is gradually stopped. The heavier the load in the carrier the greater the impetus or force with which the carrier arrives at the home or bundle-counter station and the greater the friction between the ends 35 or lugs 19' of the brackets and the forks 11, owing to the weight of the carrier and contents. In returning the carrier to the outlying station the carrier is raised, with the wire 14, upon the pulling down of the lever, so 40 that the arms or lugs 19' are raised from contact with the forks 11, permitting the carrier to move freely from the station.

Many equivalents of parts shown and described may be substituted or its equivalent 45 may be used either at the outlying or home station without departing from the spirit or scope of my invention, and I do not limit myself to the exact mechanisms or constructions shown or described.

50 Having thus described my invention, I claim as new and desire to secure by Letters Patent— :

1. The combination, in a store-service apparatus, with a station, of a wire or track 55 suitably supported therefrom and a carrier adapted to operate thereon, of means adjustably supported from said station and independent of said wire or track, extending in the path of the incoming carrier, by which 60 said incoming carrier is raised from said wire or track and noiselessly stopped and the impetus and impact thereof thereby taken up independent of said wire or track, substantially as described.

65 2. The combination, in a store-service apparatus, with a station or support, of wires 14

and 15 supported therefrom, a carrier having upper and lower wheels adapted to run against said respective wires 14 and 15, forks or arms 11 mounted on said station independently of said wires and extending in the path of the incoming carrier and adapted to raise said carrier from contact with said wires, and means whereby said wire may be raised to lift said carrier from said forks or arms 75 and propel the same out over said wires, substantially as described.

3. In a store-service apparatus, the combination, with a wire or track suitably supported, of a carrier or car adapted to operate 80 thereon, means for operating said car, and means supported below said wire or track and independently thereof in the path of said car whereby said car is adapted to be stopped by frictional contact therewith and all strain 85 from the impetus and impact of said carrier removed from said wire or track, substantially as and for the purpose specified.

4. In a store-service apparatus, the combination, with a wire or track, supporting 90 means therefor, a carrier adapted to operate thereon, means for operating said carrier, and friction arms or forks 11 adjustably supported in the path of said carrier and independent of said wire or track, whereby said carrier is adapted to be stopped by frictional contact therewith, substantially as described. 95

5. In a store-service apparatus, the combination, with a station, a wire or track suitably supported, and a carrier adapted to operate thereon, of means in operative connection with said station and track and mounted on said station independently of said wire or track whereby as said carrier approaches said station said carrier is raised from said 100 wire or track and its impetus and impact noiselessly taken up, and means whereby said wire or track may be raised and said carrier propelled thereon from said station, substantially as described. 105

6. In a store-service apparatus, the combination, with a station, a wire or track suitably supported, and a carrier adapted to operate thereon, of means mounted on said station independently of said wire or track in 110 operative connection with said station and track, whereby as said carrier approaches said station said carrier is raised from said wire or track and its impetus and impact thereby taken up, and means whereby after 115 said carrier is stopped said carrier may be operatively connected with said wire or track and sent out thereon, substantially as described.

7. The combination, with wires 14 and 15, 125 of a lever 6 whereon said wires are attached on respective sides of the fulcrum thereof, a suitable support wherein said lever is fulcrumed, a carrier or car adapted to operate on said wires by said lever, and forks or arms 130 adjustably mounted on said support and adapted to raise the incoming carrier from

said wires and take up its impetus and impact, substantially as described.

8. The combination, with a suitable support, of a lever fulcrumed therein, wires 14 and 15 attached to said levers at opposite sides of said fulcrum, a car or carrier adapted to operate on said track, parallel arms or forks 11 supported in the path of the incoming carrier, said arms or forks adjustably mount-

ed in grips provided on arms 9 supported on 10 said support, substantially as described.

In testimony whereof witness my hand, at Minneapolis, Minnesota, this 8th day of October, A. D. 1900.

CHARLES J. MILLER.

In presence of—

FREDERICK S. LYON,
G. E. STOCKING.
